US0D1049375S

(12) **United States Design Patent** (10) **Patent No.:** **US D1,049,375 S**
(45) **Date of Patent:** **** Oct. 29, 2024**

(54) **HANDHELD ENDOSCOPE**

(71) Applicant: **Zhengzhou Runde Dellonscope Co., Ltd**, Henan (CN)

(72) Inventors: **Jingzhao Sun**, Henan (CN); **Shouyun Yang**, Henan (CN)

(73) Assignee: **Zhengzhou Runde Dellonscope Co., Ltd**, Henan (CN)

(**) Term: **15 Years**

(21) Appl. No.: **29/764,105**

(22) Filed: **Dec. 28, 2020**

(30) **Foreign Application Priority Data**

Nov. 5, 2020 (CN) 202030668347.X

(51) **LOC (14) Cl.** **10-05**

(52) **U.S. Cl.**

USPC **D10/104.1**; D24/138

(57) **CLAIM**

The ornamental design for a handheld endoscope as shown and described.

DESCRIPTION

FIG. 1 is a perspective view of a handheld endoscope showing our new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines depict portions of the handheld endoscope that form no part of the claimed design.

1 Claim, 7 Drawing Sheets
